UNITED STATES PATENT OFFICE.

THOMAS G. FLEMING, OF HANOVER, OHIO.

STANCHION.

SPECIFICATION forming part of Letters Patent No. 349,578, dated September 21, 1886.

Application filed March 6, 1886. Serial No. 194,300. (No model.)

To all whom it may concern:

Be it known that I, THOMAS G. FLEMING, a citizen of the United States, residing at Hanover, in the county of Licking and State of Ohio, 5 have invented a new and useful Improvement in Stanchions, of which the following is a specification, reference being had to the accompanying drawings.

My invention relates to an improvement in 10 stanchions; and it consists in the peculiar construction and combination of devices, that will be more fully set forth hereinafter, and particularly pointed out in the claim.

In the drawings, Figure 1 is a perspective 15 view of my invention. Fig. 2 is a vertical sectional view of the same.

A represents a suitable frame or support, which is located at the head of the stall, and B represents the stanchion, which is pivoted 20 vertically therein.

a represents the lower head-block, secured 25 between parallel horizontal bars $m m'$, to one of which bars is secured the lower end of a vertical bar, b, which extends to the upper head-block, c, where it is secured between the parallel bars $n n'$. These upper and lower head-blocks, a c, extend or project beyond their respective bars $m m'$ and $n n'$, so that the latter and the frame are prevented from coming in 30 contact with the outer stationary frame, A, and binding upon the same, as will be readily understood, and the upper head-block, c, is also secured or clamped between the parallel bars $n n'$. The bar m' of the lower head-block is 35 longer than the bar m , and to the extended end of the bar m' is secured a rigid brace-bar, d, which has its upper end secured to the bar n' of the upper head-block. A small block, o, is secured between the outer ends of the bars $n 40 n'$, to close the space between the bars and prevent displacement of a pivoted bar, e, hereinafter described. This bar e is pivoted at its lower end between the bars $m m'$ at a suitable distance from the bar b, and has its upper end 45 working in the space between the bars $n n'$.

f designates a latch which is pivoted between the bars $n n'$, and having its engaging end notched to rest upon a cut-out portion of the block c. The pivoted bar e fits in the space 50 between the block c and the shoulder forming the notch of the latch f, so that should any lateral pressure be applied to the bar e the latter will act against the shoulder of the latch and serve to force its inner end down into

place upon the head-block c. The head-block 55 c thus forms a support for the latch f. The head-blocks a and c are constructed with projecting portions a' c', respectively, their office being to keep the stanchion from contact with the frame A, as hereinbefore described. Vertically-aligned pivot-bolts g pass through the head-blocks a c into the frame A, and thereby permit the stanchion to freely turn on the said frame. By tripping the latch f the upper end of the pivoted bar e is disengaged, and the said 60 bar may then be swung into the position shown in Fig. 2.

The operation of my invention is as follows: The cow to be secured in the stanchion is driven 70 into the stall and caused to pass her head between the bars b and e, and the bar b is then moved to a vertical position parallel with the bar e, when the pivoted latch f, by its own gravity, engages the upper end of the pivoted bar, and thereby locks it in position and secures the cow firmly to the stanchion, while permitting her to freely raise or lower her head, or lie down, or assume any desired position. 75

I lay special claim on the fitting of the small head-blocks a c between parallel bars, and projecting outward from the bars, as by that means the bars are retained at a proper distance from the frame A and all possibility of the stanchion binding is obviated. 80

Having thus described my invention, I 85 claim—

A stanchion comprising the bars $n n'$, the head-block c, fitted between the bars, in combination with the bars $m m'$, the block a, fitted between the bars $m m'$, both of said blocks a 90 c being extended outward from their respective bars, and having holes for the passage of pivotal bolts, the vertical bar b, connecting one end of the bars $m m' n n'$, the rigid brace-bar d, connecting the other end of bars $m' n'$, 95 the latch-bar e, pivoted at its lower end between the bars $m m'$ and working at its upper end between the bars $n n'$, and a latch, f, engaging with the latch-bar e and resting upon the head-block c, as set forth. 100

In testimony that I claim the foregoing as my own I have hereto affixed my signature in presence of two witnesses.

THOMAS G. FLEMING.
